UNITED STATES PATENT OFFICE.

MATTHEW ANDIS, OF RACINE, WISCONSIN.

ELECTRICALLY-OPERATED HAIR CLIPPER.

Application filed July 5, 1923. Serial No. 649,594.

To all whom it may concern:

Be it known that I, MATTHEW ANDIS, a citizen of the United States, residing at Racine, county of Racine, and State of Wisconsin, have invented new and useful Improvements in Electrically-Operated Hair Clippers, of which the following is a specification.

My invention relates to improvements in electrically operated hair clippers.

The objects of my invention are to provide a more efficient mechanism; to provide a form of construction adapted to permit the width of the casing to be reduced to a minimum and its shape conformed to the requirements of a handle, whereby it may be held in the hand of the operator for considerable periods without fatigue; to provide means for efficiently utilizing an alternating electric current to actuate the movable cutter or blade and to regulate the stroke and the pressure of the blades upon each other; to provide an improved blade actuating member or lever; to provide improved means for connecting said member with the blade; and to provide an improved spring mechanism for supporting and retracting the lever.

A further object of my invention is to provide a less expensive, more durable, more efficient, and more easily regulated electrically driven hair clipper.

In the drawings:

Figure 1 is a plan view of my improved hair clipper with the casing cap removed.

Figure 2 is a side view of the same with portions of the side wall broken away.

Figure 3 is a detail view of the actuator mounting in rear elevation.

Figure 4 is a plan view of the actuator and its mounting in assembled relation.

Figures 5, 6, 7, and 8 are cross sectional views drawn respectively on lines 5-5, 6-6, 7-7, and 8-8 of Figure 4.

Figure 9 is a sectional view drawn on line 9-9 of Figure 2.

Figures 10 and 11 are respectively end and plan views of the laminated magnet core.

Like parts are identified by the same reference characters throughout the several views.

The casing 1 is preferably formed of aluminum. It is provided with a downwardly inclined open ended front portion 2 having bearings to receive a stationary

blade 3. This blade is secured to the casing by screws 4. The co-operating movable blade 6 is interposed between the upper portion of the blade 3 and the end of the casing, and this movable blade is provided on its inner face with a raised bearing 7 substantially centrally disposed. Clips 8 are formed to embrace the respective ends of this bearing, and screws 9 connect the clips and the bearing with the blade 6. The clips comprise strips of resilient material having upwardly and rearwardly projecting portions, the ends of which are reversely turned to form yielding bearings 10 between which a forked connecting member 11 may be engaged. The arms 12 of the fork extend downwardly at the respective sides of the bearing member 7, whereby the blade 6 is held in position on the blade 3 and in pressure relation thereto.

The connecting member 11 extends downwardly and forwardly from the elbowed portion 13 of a laminated armature or actuator arm 14 which extends along one side of the casing 1, and connecting member 11 is secured by a clip 15 and bolts or rivets to the elbowed portion 13 of the armature. The clip 15 may be an integral portion of the connecting member 11, stamped or struck up therefrom.

The rear end portion of the actuator arm 14 is connected by a clip 16 with a reversely looped flat spring 17, disposed with its wider dimension in vertical planes, and having its opposite end secured within a mounting bracket 20 by the screw 21 and clamping nut 22. The central or forwardly projecting loop 18 of the flat spring 17 bears against an inturned lip 19 on the bracket 20. A coiled compression spring 25 is interposed between the loop 18 and the clip 16, whereby the pressure of this spring 25 will be exerted to urge the actuating arm toward the side of the casing along which its portion 14 extends.

An electromagnet is interposed between the portion 14 of the actuator arm and the opposite side of the casing 1. This electromagnet has a flat laminated core 30 of the horseshoe type, one leg of which projects through an oval winding 31 with its polar extremity 32 in proximity to the intermediate portion of the actuator arm 14. The other leg extends along the front side of the winding with its polar extremity 32' in proximity to the end of the actuator arm to

which the clip 15 is connected. Screws 34 connect the intermediate portions of the core 30 with the supporting pier blocks 33.

With the described construction, it is obvious that when the magnet is energized, the actuator arm 14 will be drawn toward the polar extremity 32 of the magnet core, the arm 14 serving as an armature. As soon as the magnet is de-energized, the arm 14 swings outwardly toward the side wall of the casing under the pressure of spring 25. With a 60 cycle alternating current, a rapid vibration of the actuator arm and the associated blade 6 of the clipper is possible.

The pressure of the blade 6 upon the stationary blade 3 may be conveniently regulated by a screw 37 which has threaded bearing in bracket 20, and is adapted at its inner end to engage a bearing head or member 39 secured in the loop 18 of the spring 17. The loop 18 is fulcrumed upon a bearing projection, or lip 24, struck up from the bottom of the bracket 20. Downward pressure at the bend or front end of the loop 18 tends to tilt this loop over the fulcrum 24, thereby swinging the rearwardly extending loop or bend 17^a upwardly and causing the front end of the armature 14 to swing downwardly without interfering with its vibratory movement induced by the electromagnet. The stroke of the actuator arm 14 may be regulated by spreading the loop 18, and this may be conveniently done by a screw 40, which also has threaded bearing in bracket 20, and has a conically tapered inner end portion 42 adapted to serve as a conical wedge between the open end of the loop 18 to spread the same when the screw is turned inwardly. By spreading the sides of the loop, the arm 14 is adjusted inwardly toward the magnet core.

The electrical connections are made at the rear end of the casing through the flexible cord 45, detachably connected with the casing by the screw-threaded plug 46. Wire 47 passes directly to the coil 31 and wire 48 passes to the switch box 49, and when the switch is closed it affords a means of connection through the wire 50 with the coil. An oscillatory switch operating member 52 is mounted upon the side of the casing. This switch and its operating piece may be of any ordinary type.

It will be observed that the blades 3 and 6 have transversely extending contacting bearings 53 and 54 with an intervening cavity 55 formed by transversely recessing the opposing faces of the blades. The bearings at 53 and 54 are narrow and the cavity 55 is open at each end, thereby allowing for a transverse delivery of any hair that would otherwise tend to wedge between the blades and interfere with the shearing operation.

By employing a laminated core for the magnet and a laminated actuator arm 14, a

substantially instant de-energization is possible. A very efficient magnet is also provided, and the winding on the flat core produces an oval coil which occupies minimum space between the upper and lower walls of the casing. By offsetting the actuator arm so that its armature portion 14 may extend along one side wall of the casing, the transverse width of the casing is reduced to a minimum. The spring hinge connection 17 between the armature and the bracket 20 is offset across the rear side of the magnet and adds nothing to the width or thickness of the casing. The elbowed portion 13 extends inwardly toward the longitudinal center line of the casing at the front side of the magnet, and the downwardly and forwardly extending connecting member 11 provides convenient means for applying pressure to the movable blade 6, whereby the pressure of the blades upon each other may be regulated by the screw 37. Ventilation is provided by slots 58 in the casing.

It will, of course, be understood that the movement of the armature arm 14 to and from the magnet core or pole piece causes flexion of the spring 17 at the initial bend or rearwardly extending loop 17^a. This portion of the spring hinge has some of the characteristics of a pivotal connection but it is adapted to allow the portion 14 of the armature to be drawn flat against the pole piece or opposing end of the core 32. Owing to this fact and the length of the arm 14, between the spring hinge at 17^a and the connecting member 11, the latter is permitted to move in substantially a straight transverse line without any material cramping or binding effect between the yielding bearings 10. The movable blade 6 has its rear or lower margin free from contact with shoulders 59 formed on the casing. The forked connecting member 11 not only holds the blade in pressure contact with the relatively stationary blade 3, but also positions it and holds it against outward or inward movement. The movable blade is, therefore, wholly free to slide on the blade 3 in any direction that the actuator may move it.

The casing is preferably open at the top to afford access to the interior, a cap 38 normally closes this opening and the screws 37 and 40 extend loosely through holes in this cap. The latter is connected with the casing by screws 41.

I claim:

1. In a hair clipper, the combination of relatively movable blades, an actuator for one of the blades having a swinging end loosely interlocked therewith and provided at its other end portion with a support, and adjustable means for applying pressure to the supported end portion of the actuator in the direction of the stationary blade.

2. In a hair clipper, the combination with a support, of a stationary blade, a movable blade adapted to slide freely in any direction upon one surface of the stationary blade, an actuator having one end loosely interlocked with the central portion of the movable blade and its other end connected with the support, means for laterally swinging the actuator to impart a vibratory movement to the blade, and resilient connections for communicating said vibratory movement from the actuator to the blade. 70
3. In a hair clipper, the combination with a support, of a stationary blade, a movable blade adapted to slide freely in any direction upon one surface of the stationary blade, an actuator having one end loosely interlocked with the central portion of the movable blade and its other end connected with the support, means for swinging the actuator upon its supporting connection to impart a vibratory movement of the blade, resilient means for communicating said vibratory movement from the actuator to the blade, and means connected with the support for adjustably pressing said actuator in the direction of the movable blade to regulate its pressure upon the stationary blade. 80
4. The combination with the movable blade of a hair clipper, a set of resilient clips mounted upon the blade and provided with portions inturned, each in the direction of the other, and a vibratory actuator for the blade having a connecting portion engaged between the inturned portions of said clips, whereby the vibratory movements of the actuator may be yieldingly transmitted to the blade. 85
5. The combination with the movable blade of a hair clipper, a set of resilient clips mounted upon the blade and provided with extremities inturned, each in the direction of the other, and a vibratory actuator for the blade having a flat connecting portion substantially perpendicular to the surface of the blade and engaged between the inturned ends of said clip, whereby the vibratory movements of the actuator may be yieldingly transmitted to the blade, said flat connecting portion being also adapted to loosely interlock with the blade to prevent movement of the latter in directions transverse to its vibratory movement. 100
6. In a hair clipper, the combination with a set of co-acting hair clipping blades, of a support, an actuator for one of the blades, a looped spring connecting the actuator with the support, and electromagnetic means for moving the actuator intermittently from the normal position in which it is supported by said spring. 110
7. In a hair clipper, the combination with a set of co-acting hair clipping blades, of a support, an actuator for one of the blades, a looped spring connecting the actuator with the support, and electromagnetic means for moving the actuator intermittently from the normal position in which it is supported by said spring. 120
- a looped spring connecting the actuator with the support, and electromagnetic means for moving the actuator intermittently from the normal position in which it is supported by said spring, said looped spring comprising a flat strip of resilient metal, disposed in planes substantially perpendicular to that in which the actuator moves. 130
8. In a hair clipper, the combination with a set of co-acting hair clipping blades, of a support, an actuator for one of the blades, an electromagnet for moving the actuator in one direction, a reversely looped flat spring connecting the actuator with the support at one side of the magnet and disposed with its flat sides in vertical planes, a fulcrum member on the support, upon which one looped portion of the spring rests, adjustable means on the support for applying pressure to the opposite side of the spring between the fulcrum and the blades, and means for loosely connecting the actuator with its associated blade at the other side of the magnet and substantially at the central axis of the support. 140
9. In a hair clipper, the combination with a hollow handle, an electromagnet contained within the handle; an armature having transversely extending spring hinge connection with the handle at the rear of the magnet, and a connecting member in front of the magnet; a relatively stationary hair clipping blade secured to the front end of the handle; a co-acting movable blade loosely supported against the first mentioned blade by said connecting member; and means for applying downward pressure to the armature and movable blade to regulate the pressure of the blades upon each other. 150
10. In a hair clipper, the combination with a hollow handle, an electromagnet contained within the handle, an armature having transversely extending spring hinge connection with the handle at the rear of the magnet and a connecting member in front of the magnet, a relatively stationary hair clipping blade secured to the front end of the handle, a co-acting movable blade loosely supported against the first mentioned blade by said connecting member, means for applying downward pressure to the armature and movable blade to regulate the pressure of the blades upon each other, and means for adjusting the spring hinge connection to regulate the stroke of the armature. 160
11. In a hair clipper having a hollow handle provided with co-acting relatively movable blades at one end thereof, an electromagnet within the handle, an armature loosely connected with one of the blades in front of the magnet and having an offset central portion extending along one side of the handle to the rear of the magnet, a reversely looped flat spring disposed transversely of the handle in the rear of the handle. 170

magnet with one end connected with the handle and the other supporting the armature, and a spreader for separating the sides of one of the spring loops to vary the stroke of the armature.

12. In an electromagnetic clipper, the combination with a movable blade and a vibratory blade actuating armature, of a set of yielding clips connected with the blade, and 10 a connecting member on the armature loosely engaged between said clips and adapted to transmit the motion of the armature to actuate the blade transversely.

13. In an electromagnetic clipper the combination with a movable blade and a vibratory blade actuating armature, of a set of yielding clips connected with the blade, and 15 a connecting member on the armature loosely engaged between said clips and adapted to transmit the motion of the armature to actuate the blade transversely, said blade having a shouldered projection and said connecting member being forked and adapted to loosely engage said projection to hold the 20 blade against outward or inward movement.

14. In an electromagnetic hair clipper, a vibratory blade actuating armature, a hollow handle enclosing said armature, a transversely disposed reversely bent strip of 25 silent metal connecting the armature with the handle in spring hinge relation thereto, and a coiled spring interposed between two of the legs of one of the spring loops in a position to retract the armature by its 30 recoil.

15. In a hair clipper, the combination with a hollow handle, of a set of co-acting hair clipping blades at one end of the handle, an electromagnet within the handle, a co- 40 acting armature having one end operatively connected with one of the blades, a flat strip of resilient metal having its width in a plane perpendicular to that of armature movement and reversely looped along a line 45 transverse to the handle, one end of said strip being in supporting relation to the armature and the other end being connected with the handle.

16. In a hair clipper, the combination with a hollow handle, of a set of co-acting hair clipping blades at one end of the handle, an electromagnet within the handle, a co-acting armature having one end operatively connected with one of the blades, a 55 flat strip of resilient metal having its width in a plane perpendicular to that of armature movement and reversely looped along a line transverse to the handle, one end of said strip being in supporting relation to the 60 armature and the other end being connected with the handle, and means for spreading one of the loops of said strip to vary the position of the armature.

17. In a hair clipper, the combination

with a hollow handle, of a set of co-acting 65 hair clipping blades at one end of the handle, an electromagnet within the handle, a co-acting armature having one end operatively connected with one of the blades, a flat strip of resilient metal having its width 70 in a plane perpendicular to that of armature movement and reversely looped along a line transverse to the handle, one end of said strip being in supporting relation to the armature and the other end being connected 75 with the handle, means for spreading one of the loops of said strip to vary the position of the armature, and adjustable means for urging said strip and armature in a direction at right angles to the plane of armature 80 movement.

18. In an electromagnetic hair clipper, a transversely movable hair cutting blade, a vibratory blade actuating armature loosely connected with the blade and adapted to apply pressure thereto, a hollow handle enclosing said armature, a yielding connection between the rear end of the armature and the handle adapted to allow both downward 90 and lateral movement of the working end of the armature, an electromagnet adapted to actuate the armature transversely in one direction, an armature retracting spring adapted to move it in the other direction, and adjustable means for applying pressure to said yielding connection to vary the 95 pressure of the armature upon said blade, said yielding connection being adapted to receive such pressure without material interference with the vibratory movement of the 100 armature.

19. In a hair clipper, the combination with a support, of a relatively stationary blade, a movable blade having a smooth under surface adapted to slide freely in any direction upon the opposing surface of the stationary blade, a vibratory actuator having one end connected with the support and adapted for lateral swinging movement upon said connection, and means connected 105 with the support for applying pressure to the vibratory actuator in the direction of the stationary blade to regulate the pressure of the movable blade thereon.

20. The combination with the movable blade of a hair clipper, of a longitudinally extending projection on the outer surface of the central portion of the blade, a set of resilient clips secured to the central portion of the blade, and a vibratory blade actuator, 110 having a forked member resiliently engaged between said clips, with its fork arms loosely interlocked with said projection to hold the blade from movement transverse to its 120 cutting margin.

21. The combination with the movable blade of a hair clipper, of a set of upstanding flat clips of resilient material secured to 125

the blade, and a blade actuator having a flat connecting member engaged between the clips in resilient pressure relation thereto.

22. The combination with the movable blade of a hair clipper, of a set of upstanding flat clips of resilient material secured to the blade, a blade actuator having a flat connecting member engaged between the

clips in resilient pressure relation thereto, said clips having inturned extremities bearing against flat sides of the connecting member, and said connecting member being otherwise loosely interlocked with the blade to prevent movement upon the blade in the plane of the connecting member.

MATTHEW ANDIS.
